UNITED STATES PATENT OFFICE.

GEORGE ROCKWELL, OF MERIDEN, ASSIGNOR TO ROGERS & BROTHER, OF WATERBURY, CONNECTICUT.

DESIGN FOR A SPOON, &c.

SPECIFICATION forming part of Design No. 22,409, dated May 9, 1893.

Application filed March 10, 1893. Serial No. 465,429. Term of patent 7 years.

To all whom it may concern:

Be it known that I, GEORGE ROCKWELL, of Meriden, in the county of New Haven and State of Connecticut, have invented a new Design for the Handles of Spoons and Forks; and I do hereby declare the following, when taken in connection with accompanying drawing and the letters of reference marked thereon, to be a full, clear, and exact description of the same, and which said drawing constitutes part of this specification, and represents a face view.

My invention relates to a new and original design for handles for spoons and forks, and consists in the configuration and ornamentation of the handle as shown in the accompanying illustration.

The outer end of the handle contains a shield A, which is inclosed by scrolls B, and leaves C, which give the said end of the handle its outline. Below the said shield and

separated therefrom by other similar scrolls B and leaves C, is located a dolphin D, whose head is situated at one side of the axial center of the handle, across which its body extends obliquely, over and under the same, its tail reappearing upon the upper face of the handle, the extreme inner end of which has a simple leaf-like ornamentation E.

The whole configuration and ornamentation of the handle belong to the rococo style of decoration.

I claim—

The design for handles of spoons and forks as herein described and shown.

In testimony whereof I have signed this specification in the presence of two subscribing witnesses.

GEO. ROCKWELL.
